UNITED STATES PATENT OFFICE.

WILBUR S. UPSON, OF MANSFIELD, OHIO.

WRENCH.

1,206,947.

Specification of Letters Patent.

Patented Dec. 5, 1916.

Application filed March 2, 1916. Serial No. 81,723.

To all whom it may concern:

Be it known that I, WILBUR S. UPSON, a citizen of the United States of America, residing at Mansfield, in the county of Rich-
5 land and State of Ohio, have invented cer-
tain new and useful Improvements in
Wrenches, of which the following is a speci-
fication.

This invention relates to wrenches of the
10 type comprising a stationary jaw and a co-
operating, sliding, adjustable jaw, adapted
for use in fastening and loosening different
sizes of nuts, bolts and the like.

The primary object of this invention is to
15 provide means of rapidly, conveniently and
slidably adjusting the movable jaw of the
wrench to fit various sizes of nuts and bolts
and means automatically operable when the
20 shank of the stationary jaw and the pivoted
lever handle are grasped by the user of the
wrench in manipulating it to perform its
functions to rigidly maintain the movable
jaw in its adjusted position in juxtaposition
25 to the nut or bolt during the operation of
fastening or loosening the bolts or nuts.

Another feature of this invention consists
in the means employed of pivotally attach-
ing a lever handle to the body portion of
30 the stationary jaw and utilizing it to per-
form the combined functions of a handle
and to provide means of co-acting with
other means to clamp the movable jaw in a
predetermined or adjusted position.

A further object is to provide a positive
35 stop for the inward throw of the lever
handle.

The preferable specific construction used
to accomplish the above described objects
comprise means of pivotally attaching a le-
40 ver handle to the body portion of the sta-
tionary jaw, and interposing a pivoted
ratchet pawl between the end of the lever
handle and the face of the shoe of a mov-
able jaw which is provided with a series of
45 ratchet teeth that correspond with the
ratchet teeth of the pivoted pawl, the end
of the lever handle being so located and
arranged as to force the teeth of the pawl
and shoe to mesh at any adjusted position
50 of the movable jaw when it is grasped for
manipulation by the user in connection with
the shank of the stationary jaw.

These and other objects are attained by
the mechanism illustrated in the accom-
55 panying drawing, in which:

Figure 1 is a vertical side elevation partly
in section of the wrench showing the teeth

of the pivoted ratchet pawl in mesh with
the ratchet teeth provided on the shoe of
the movable jaw. Fig. 2 is an edge view of 60
Fig. 1. Fig. 3 is a vertical side elevation of
the wrench showing a part of the body por-
tion of the stationary jaw broken away to
clearly show the inoperative position of the
lever handle permitting the teeth of the 65
pivotal ratchet pawl to drop or be yield-
ingly drawn out of mesh with the teeth of
the shoe of the movable jaw.

In the drawings reference numeral 1 rep-
resents a stationary jaw, 2 the body portion 70
of the jaw and 3 a shank preferably formed
integral with the body portion. A movable
jaw 4 is provided having an integral shoe 5
which slidably fits a guideway 6 formed in
the body portion of the stationary jaw. The 75
guideway is preferably formed at an angle
to the body portion of the stationary jaw
and shank.

One end of a lever handle 8 is secured to
a pin 9 to pivot within a recess 10. The 80
end 11 of the lever handle is preferably
tapered. A pawl 12 having a series of ratchet
teeth is pivoted with the recess 10 upon a
pin 14 and so arranged and located as to be
interposed between the end 11 of the lever 85
handle 8 and the shoe of the movable jaw.

The spring 15 normally exerts its tension
to maintain the rib or projecting portion 16
in contact with the end 11 of the lever han-
dle. A series of ratchet teeth 17 is pro- 90
vided on the shoe in aligned position with the
ratchet teeth of the pawl 12. A stop mem-
ber 18 is secured to the shank 3 and is pro-
vided with a notch 19 to yieldingly engage
the pin 20 which is secured to the lever han- 95
dle 18 as shown in Fig. 1.

To prevent excessive outward movement
of the movable jaw 4, a screw 21 is arranged
to present the head thereof in contact with
the end of the movable jaw. 100

The operation or manipulation of the
above described wrench for the purpose in-
tended is as follows: The user adjusts the
movable jaw 4 to fit the nut or bolt it is de-
sired to fasten or loosen and then grasps the 105
lever handle 8 and shank 3 pressing them
toward each other, the swing or pivotal
movement of the lever handle caused thereby
forces the end 11 to contact with, and to
exert a pressure against the rib 16 forcing 110
the pawl 12 to pivot upon the pin 14 and
the teeth 13 formed thereon to mesh with
the teeth 17 formed on the sliding shoe,
thereby rigidly maintaining the movable

jaw in its adjusted position. The end 11 of the lever handle is so proportioned and located with respect to the rib 16 that when the end is at or a trifle over the center of the horizontal axis of the rib, the notch 19 will engage the pin 20 and positively stop further movement of the lever handle 8 and shank 3 toward each other, as shown in Fig. 1. The rib and end 11 of the lever handle also assist in yieldingly locking the lever handle and shank together. When it is desired to release the movable jaw from its adjusted position, the lever handle is swung outward as shown in Fig. 3 releasing the end 11 of the lever handle from its contact with the rib, and the pawl is forced to pivot by the spring 15 and withdraw the teeth 13 from their mesh with the teeth 17 formed on the shoe.

20 What I claim is:

1. In a wrench, a stationary jaw having a body portion provided with a recess and a shank, a guideway formed in the body portion, a movable jaw carrying a shoe having ratchet teeth provided thereon slidably fitted in the guideway, a lever handle having one end pivoted to swing within the recess, a pivoted ratchet pawl interposed between the pivoted end of the lever handle and the shoe of the movable jaw which is adapted to contact with the end of the lever handle and be forced thereby, to mesh with the teeth provided on the shoe of the movable jaw to rigidly maintain same in its adjusted position when the handle and shank are grasped by the user and pressed toward each other.

2. In a wrench, a stationary jaw having a body portion provided with a recess and a shank, a guideway formed in the body portion, a movable jaw carrying a shoe having ratchet teeth provided thereon, slidably fitted in the guideway, a lever handle having one end pivoted to swing within the recess, a pivoted ratchet pawl interposed between the pivoted end of the lever handle and the shoe of the movable jaw which is adapted to contact with the end of the lever handle and be forced thereby, to mesh with the teeth provided on the shoe of the movable jaw thereby rigidly maintaining same in any adjusted position when the handle and shank are grasped by the user and pressed toward each other, and pins arranged to engage at right angles to each other to stop the inward swing of the lever handle at a pre-determined point with respect to the shank.

50 3. In a wrench, a stationary jaw having an integral recessed body portion and a shank, a lever pivoted in said recess, an angularly related guideway formed in the body portion, communicating with said re-

cess, a movable jaw having a shoe slidably fitted in said guideway, and pivotally mounted means interposed between the end of the lever handle and shoe which contacts with and is operable by the end of the lever handle only, to hold and maintain the movable jaw at any point of its adjustment.

4. In a wrench, a stationary jaw and a shank, a coöperative movable jaw, a pivoted lever handle, pivotally mounted means interposed between the movable jaw and the end of the lever handle adapted to contact with the movable jaw and the end of the lever handle, and which is operable by pressing the shank and lever handle toward each other to maintain the movable jaw at any point of its adjustment.

5. In a wrench, a stationary jaw and a shank, a coöperative movable jaw provided with a shoe, a pivoted lever handle, pivotally mounted means interposed between the shoe of the movable jaw and the end of the lever handle which contacts with the lever handle and is operable by pressing the shank and lever handle toward each other to maintain the movable jaw through the medium of the pivoted means only at any point of its adjustment, and right angularly related pins to yieldingly interlock the shank and lever handle at a pre-determined point of their movement toward each other.

6. In a wrench, a stationary jaw and a shank, a coöperative movable jaw provided with a shoe, a pivoted lever handle, pivotally mounted means interposed between the shoe of the movable jaw and the end of the lever handle to contact with the lever handle and which is operable by pressing the shank and lever handle toward each other to maintain the movable jaw at any point of its adjustment, pins secured to the shank and lever handle to yieldingly interlock the shank and lever handle at a pre-determined point of their movement toward each other, and means arranged on the body portion of the wrench to prevent excessive outward movement of the movable jaw.

7. In a wrench, a stationary jaw provided with a recess and a shank, a guideway provided in the stationary jaw, a movable jaw having a shoe provided with ratchet teeth slidably fitted in said guideway, a ratchet pawl pivoted in said recess, a lever handle pivoted to permit its end to swing within said recess; said lever handle contacting with and exerting a pressure upon the pawl to force the teeth of the pawl and teeth of the shoe to mesh at any point of the adjustment of the movable jaw.

In testimony whereof I affix my signature.

WILBUR S. UPSON.
